PORTABLE SHOWER BATH

Filed Sept. 16, 1940

UNITED STATES PATENT OFFICE

2,236,376

PORTABLE SHOWER BATH

Harry F. McClendon, Denver, Colo.

Application September 16, 1940, Serial No. 356,892

2 Claims. (Cl. 4—147)

This invention relates to improvements in portable shower baths.

Hotel and rooming house proprietors find that the public demands a shower bath and that rooms 5 provided with shower baths rent more readily and at a higher rate, than similar rooms provided with tubs.

In many hotels and rooming houses, shower baths have not been provided and to equip such 10 rooms with shower baths connected with the plumbing and with the sewer involves a great expense per room which oftentimes makes it prohibitive.

It is the object of this invention to produce 15 a portable shower bath that can readily be connected with the hot and cold water faucets already provided in the rooms, and which shall be provided with means for elevating the water so as to discharge the used water into a wash basin 20 or sink, thereby obviating the necessity of providing a sewer connection from each of the shower baths.

I am aware that portable shower baths have 25 been suggested which, however, are so constructed that the used water is discharged through a hose which extends through a door or other opening and depends on gravity for producing a flow or in which the drain from the shower bath is connected directly with the sewer system. Such 30 shower baths are expensive to install and cannot be transferred from one room to the other, which makes the provision of such auxiliary baths prohibitive for most hotels and rooming houses.

It is an object of this invention to produce 35 a portable shower bath comprising a tank having a drain and having means for enclosing the bather and for providing a spray of water for the shower. The drain, instead of being connected with the 40 sewer is connected with the intake of a pump or other water elevating device, such as an injector syphon which raises the water to any desired elevation, whereby the discharge outlet from such water elevating device can be connected directly with a wash basin or bath tub by 45 means of a flexible hose.

Another object of this invention is to produce 50 a portable bath of a type indicated in which the water tank shall be provided with a hinged lateral extension along one side that can be folded into position within the tank when not in use and can be folded outwardly when in use, whereby the size of the enclosure can be readily varied so as to increase the same when the bath is in use and to reduce the size to a minimum during transporta- 55

tion and during such times as the bath is not in use.

Another object of this invention is to produce a portable bath of the type indicated of such construction that it can readily be "knocked down" 5 for shipment and be readily re-erected, whereby a large saving in freight can be had over portable shower baths that are not so constructed.

Another object of this invention is to provide a shower bath of the type described in which the water for the spray is controlled by a valve so situated that it may be operated by the person using the bath and which shall be so associated with the water elevating device that the latter will be sure to function whenever the spray is operating, thereby assuring that the tank will not overflow. The above and other objects that may become apparent as this description proceeds are attained by means of a construction and an arrangement of parts that will now be described in detail and for this purpose reference will be had to the accompanying drawing in which one form of the invention has been illustrated, and in which:

Figure 1 is a front elevation of the shower bath 25 looking in the direction of arrow 1, in Figure 2;

Figure 2 is a side elevation looking in the direction of arrow 2, in Figure 1;

Figure 3 is a transverse section taken on lines 30 3—3, Figures 1 and 2;

Figure 4 is a fragmentary, transverse section taken on line 4—4, Figure 5;

Figure 5 is a section taken on line 5—5, Figure 4;

Figure 6 is a detail showing in a general manner the water elevating means comprising a syphon or injector;

Figure 7 is a fragmentary section taken on line 7—7, Figure 3; and

Figure 8 is a section taken on line 8—8, Figure 7. 40

In the drawing reference numeral 10 designates the floor of a room on which the portable shower bath is supported. The bath consists of a tank of substantially square or rectangular shape, the front wall of which has been designated 45 by reference numeral 11. The end walls have been designated by reference numerals 12 and the rear wall by reference numeral 13. The tank may be made from boards and lined with sheet metal or it may be made entirely from sheet 50 metal or from any other suitable material. Secured to each corner of the tank is an angle iron 14. The angle irons may be made from aluminum and will therefore be light and strong. The upper ends of the angle irons are connected by 55

means of a rod 15 on which is slidably mounted a number of rings 16 that support a curtain 17 made from some water proof material such as a rubber sheet of the type sold under the trade name of "pliofilm." The angle iron supports may be connected by one or more rods 18 extending from the front angle irons around the rear of the frame. In order to brace the frame a rearwardly extending bracket 19 may be provided and 10 to the rear of this the lower end of a brace member 20 may be connected by a bolt or other means 21. The brace member 20 forms with the two rear corner angle irons a triangular structure as shown in Figure 2. In addition to this bracing means, 15 other braces, like those indicated by reference numeral 22, may be provided, if desired. The bottom of the tank is provided with a drain opening 23 that communicates with the lower end of a drain pipe 24 when the water elevating means 20 embodies a siphon or injector like that illustrated in Figure 6. If an electric pump is employed for elevating the water, the drain 24 communicates with a shallow tank whose bottom has been designated by reference numeral 25, and a centrifugal pump 26 is secured to the bottom 25 with its intake ports 27 in communication with the compartment whose bottom is designated by reference numeral 25. The outer wall 27' of the pump compartment should extend to the top of the tank 30 as shown most clearly in Figure 4. An electric motor 28 is supported by the vertical angle irons 14 and is provided with a shaft 29 that connects the motor to the impeller of the centrifugal pump. The outlet port of the pump is connected to the 35 lower end of a hose 30 which conveys the water to a wash bowl 31 or other fixture connected with the sewer. Water for the spray is conducted to the spray head 32 by means of a pipe 33 which is secured to the frame and in which is positioned 40 a globe valve 34 which serves to control the flow of water to the spray head. The valve is controlled by means of a handle 35 so positioned that it is accessible from the front of the cabinet. The water is supplied to the valve by means of a 45 pipe 36 that is connected to a hose 37 which is provided with a Y fitting 38 from which a hose 39 extends to the hot water faucet 40 and a similar hose 41 connects with the cold water faucet 42. When the valve 34 is open, water will be 50 conveyed directly to the sprinkler head and must be properly proportioned by means of faucets 40 and 42 so as to get the desired temperature.

Referring now more particularly to Figure 6 in which the valve has been shown broken away, 55 it will be observed that the chamber 43 is connected with the nozzle 44 of an injector siphon 45. The intake of this siphon is connected with a drain 23 by a pipe 24 and the outlet from the siphon is connected to a hose 39 that conveys the 60 water to the bowl 31.

It will now be apparent that whenever the faucets 40 and 42 are open, water will flow into chamber 43 and through the nozzle 44, thereby setting up the suction in pipe 24. The water that 65 is discharged into the hose 31 flows to the water basin as clearly shown in Figure 2. When valve 34 is open water will flow to the sprinkler head as above described. For the purpose of providing more room within the cabinet an extension 46 70 has been provided and this is connected with the front wall 11 of the tank by means of hinges 47. The ends of extension 46 are preferably bent upwardly at right angles as indicated by reference numeral 48 and the front edge is bent vertically 75 as designated by reference numeral 49. The in-

ner ends of the end members 48 are bent laterally as shown at 50 so as to engage the flanges of the corner angle irons 14. The upturned ends 48 and the outer upturned edge 49 serve to hold the covering 17 from sliding out and assures that 5 any water deposited on the inner surface thereof will be returned to the tank.

Referring now to Figure 4, reference numeral 35 designates the handle of valve 34 and to this a switch arm 51 has been frictionally secured. 10 This switch arm has been shown as forming the movable part of an electric switch whose stationary contact has been designated by reference numeral 52. The source of electricity has been indicated by a battery 53 which is connected to one 15 terminal of the motor by a conductor 54, the other terminal of the battery is connected with contact 52 by means of a wire 55 and switch arm 51 is connected with the other motor terminal by means of a conductor 56. The parts are so arranged that when the valve 34 is open, the switch contacts 51 and 52 engage so as to close the circuit to the motor, thereby assuring that the motor will always operate whenever the valve is open. A stop 57 limits the movement of switch 20 arm 51 and its frictional connection with the stem of handle 35 permits the latter to be turned to any extent. The switch arrangement just described is diagrammatic only and intended to illustrate a switch mechanism controlled by the 25 operation of valve 34 and instead of the specific mechanism shown any other suitable mechanical-ly equivalent device may be substituted.

In the embodiment illustrated, the shower bath 35 cabinet has been shown as provided with a water proof curtain 17 which is believed to be a desirable construction, but it is to be understood that other specifically different material may be employed for this purpose as, for example, the walls may be made from linoleum or metal, plywood or any 40 other suitable material and applicant does not want to be limited to a curtain for this purpose.

It is apparent from the above description that a shower bath cabinet constructed in the manner shown and described can be readily transported 45 and can be moved from room to room, if desired, and that it can be quickly connected with the hot and cold water that is provided in connection with the wash bowl 31. The hose 33 is merely so positioned that it discharges the water into the 50 bowl 31 and therefore no expensive connections with the sewer becomes necessary. Where an electric motor is employed, suitable connections must, of course, be made with the lighting circuit, but this can be effected by means of a plug 55 and extension cord in the usual manner.

The flexible hose 39 and 41 are provided with clamping means 58 that positively secure them to the faucets 40 and 42. Supported on the bottom of the tank is a perforated board 59 that is spaced 60 from the bottom and serves as a support for the bather.

Having described the invention what is claimed as new is:

1. A portable shower bath comprising, a shallow 65 tank, frame members secured to the tank and extending upwardly therefrom, a drain board hinged to the upper edge of one side of the tank, said drain board being movable into a position in which it extends beyond the outer surface of the 70 side, the ends of the drain board having upwardly extending end walls, and means comprising outwardly extending stops for engaging the adjacent frame members to limit the outward movement of the drain board.

2. A portable shower bath comprising, a shallow tank and extending upwardly therefrom, certain supporting rods interconnecting the upper ends of the frame members, a support projecting from the tank to a point beyond a line joining two frame members, a brace having its lower end

5 attached to the support and its upper end connected with the frame members adjacent their upper ends whereby a stress triangle is formed, which resists relative movement between the tank and the frame in one plane.

HARRY F. McCLENDON.
